(57) **CLAIM**

The ornamental design for a supplemental reverse lighting unit, as shown and described.

DESCRIPTION

FIG. 1 is a front perspective view of a supplemental reverse lighting unit showing one embodiment of our new design;
FIG. 2 is rear perspective view of the embodiment of FIG. 1;
FIG. 3 is a front elevational view of the embodiment of FIG. 1;

FIG. 4 is a rear elevational view of the embodiment of FIG. 1;

FIG. 5 is a right side elevational view of the embodiment of FIG. 1;

FIG. 6 is a left side elevational view of the embodiment of FIG. 1;

FIG. 7 is a top plan view of the embodiment of FIG. 1;
FIG. 8 is a bottom plan view of the embodiment of FIG. 1;
FIG. 9 is a front perspective view of a supplemental reverse lighting unit showing a second embodiment of our new design;

FIG. 10 is rear perspective view of the embodiment of FIG. 9;

FIG. 11 is a front elevational view of the embodiment of FIG. 9;

FIG. 12 is a rear elevational view of the embodiment of FIG. 9;

FIG. 13 is a right side elevational view of the embodiment of FIG. 9;

FIG. 14 is a left side elevational view of the embodiment of FIG. 9;

FIG. 15 is a top plan view of the embodiment of FIG. 9;

FIG. 16 is a bottom plan view of the embodiment of FIG. 9;

FIG. 17 is a front perspective view of a supplemental reverse lighting unit showing a third embodiment of our new design;
FIG. 18 is rear perspective view of the embodiment of FIG. 17;

FIG. 19 is a front elevational view of the embodiment of FIG. 17;

FIG. 20 is a rear elevational view of the embodiment of FIG. 17;

FIG. 21 is a right side elevational view of the embodiment of FIG. 17;

FIG. 22 is a left side elevational view of the embodiment of FIG. 17;

FIG. 23 is a top plan view of the embodiment of FIG. 17; and,

FIG. 24 is a bottom plan view of the embodiment of FIG. 17.
